(57) CLAIM

The ornamental design for a cosmetics container as shown and described.

DESCRIPTION

FIG. 1 is a front, left, top perspective view of a cosmetics container with the lid open showing the new design.

FIG. 3 is an exploded front, left, top perspective view of the cosmetics container of FIG. 2.

FIG. 4 is a top plan view of the cosmetics container of FIG. 2.

FIG. 5 is a front, left, top perspective view of the cosmetics container of FIG. 1 shown in an alternate configuration with the lid closed.

FIG. 6 is a bottom plan view of the cosmetics container of FIG. 1 shown in an alternate configuration with the lid closed.

FIG. 7 is a top plan view of the cosmetics container of FIG. 1 shown in an alternate configuration with the lid closed.

FIG. 8 is a rear, left, bottom perspective view of the cosmetics container of FIG. 1 shown in an alternate configuration with the lid closed.

FIG. 9 is a front elevation view of the cosmetics container of FIG. 1 shown in an alternate configuration with the lid closed.

FIG. 10 is a rear elevation view of the cosmetics container of FIG. 1 shown in an alternate configuration with the lid closed.

FIG. 11 is a left side elevation view of the cosmetics container of FIG. 1 shown in an alternate configuration with the lid closed; and,

FIG. 12 is a right side elevation view of the cosmetics container of FIG. 1 shown in an alternate configuration with the lid closed.

The broken lines in the figures represent portions of the cosmetics container that form no part of the claimed design.

1 Claim, 12 Drawing Sheets
